UNITED STATES PATENT OFFICE.

CHARLES MCNEIL, OF GLASGOW, SCOTLAND.

DUMBTURNER FOR SUGAR-CANE MILLS.

Application filed July 26, 1922. Serial No. 577,728.

To all whom it may concern:

Be it known that I, CHARLES MCNEIL, B. Sc., a British subject, and a resident of Glasgow, Scotland, engineer, have invented 5 certain new and useful Improvements in Connection with Dumbturners for Sugar-Cane Mills, of which the following is the specification.

This invention relates to the dumbturners 10 and bars for carrying same, placed between the two lower rolls of a three-roll sugar-cane mill to direct the cane through the mill, the parts being adjustable relatively to the rolls by wedges carried by bolts and acting between parts on each side of each end of the bar and projections on the housings of the mill, the carrying bolts being adjustably held in the housing so that they pass downwards from the wedges. As usually constructed, the dumbturner plate is checked on its under side into the upper surfaces of its carrying bar so that it and the carrying bar are moved together as one piece to or from the front roll on movement of the adjusting wedges; and the invention has for its object to improve the construction of the dumbturner plate and carrying bar so that the dumbturner plate itself may be separately adjustable relatively to the rolls, irrespective of the adjustment of the carrying bar, the invention being applicable to either the rocker bar type of dumbturner or to what is known as the fixed bar type.

A dumbturner made according to the invention comprises essentially a carrying bar 35 adjustably held as usual by wedges acting between parts on the bar and projections on the mill housings, and a dumbturner plate separate from the carrying bar, means for separately adjusting this plate relatively to the rolls irrespective of the adjustment of the carrying bar, and means for holding the dumbturner plate on the upper surface of the carrying bar.

Two illustrative examples of the invention are shown on two accompanying sheets of explanatory drawings, Figure 1, Sheet 1, being an elevation of the inner side of one headstock, and Figure 2 a sectional front elevation showing parts of a three-roll sugar-cane mill, sufficient to illustrate the first

example, whilst Figures 3 and 4, Sheet 2, are views similar to Figures 1 and 2, showing the second example.

According to the example shown in Figures 1 and 2, there is provided a dumbturner plate A which extends laterally beyond the usual flange B on the upper roll B¹ of the mill, the plate having in its upper surface a groove A¹ into which the flange extends. The under surface of the plate A is inclined from the front upwards towards the rear and rests on a counterpart inclined portion C on the upper surface of the usual carrying bar C¹, being held on that bar by a number of transverse dove-tailed ribs A² on its under side, engaging counterpart dove-tailed slots C² in the top of the carrying bar. The dove-tailed ribs and slots, whilst holding the plate A on the bar C¹, permit of transverse movement of the plate relative to the bar, as hereinafter described. It is to be understood that the ribs A² and slots C² may be reversed if desired, that is, the ribs may be on the carrying bar C¹ and the slots in the underside of the dumbturner plate A. At each end of the dumbturner plate A there is formed on its upper surface a wedge face A³ oppositely inclined to the inclination on the under side of the plate, that is, it extends from the front downwards towards the rear. With these upper surfaces there engage counterpart inclined wedges D lying between them and projections D¹ on the inner faces of the housings. These wedges D have connected to their forward sides rods D² extending out to the front of the mill where they pass through brackets or lugs D³ on the housings. The rods are screwed at their outer ends and held in place by nuts D⁴ on opposite sides of the lugs D³. Rods E also extend from the rear of the dumbturner plate at each end thereof to similar brackets or lugs E¹ towards the rear of the housings. The outer ends of these rods are also screwed to receive adjusting nuts and washers E² on opposite sides of the lugs E¹. The carrying bar C¹ is of the fixed bar type and is adjustable relative to the rolls as usual, by wedges G carried by bolts G¹ and acting between inclined parts on each side of each end of the

- bar, and projections G^2 on the housing of the mill, the carrying bolts being adjustably held in lugs G^3 on the inner face of the housing.
- 5 When in use, and the gap between the front lower roll H and the upper roll B^1 has been adjusted in usual manner, and after the wedges G holding the carrying bar C^1 have been screwed up to hold that bar rigid
- 10 as usual, the rods E extending rearwards from the dumbturner plate A are adjusted until the forward knife edge on that plate is bearing on the surface of the front roll H , then the wedges D bearing on the wedge
- 15 faces A^3 on the opposite ends of the upper side of the plate A are also tightened up, this tends to impart a forward pull to the plate and thus ensures that when the cane is passing through between the lower and
- 20 upper rolls there will be no tendency for the cane to get between the lower front roll H and the knife edge of the plate, and thus damage it; also, should the usual horizontal bolts (not shown) holding the headstock side
- 25 caps J stretch when the mill is in use, as they may do, and thus alter the position of the front roll H relative to the plate A , further adjustment of the dumbturner plate A itself is readily effected without stopping
- 30 the mill, which it is necessary to do with existing constructions (where the plate and its carrying bar move as one) in order to get below the mill to the bolts G^1 carrying the usual adjusting wedges G for the bar C^1 .
- 35 The example shown in Figures 3 and 4 differs from that hereinbefore described only in that instead of the dumbturner plate A being held on its carrying bar C^1 by dove-tailed ribs A^2 and slots C^2 , the plate A rests
- 40 on the counterpart inclined portion C on the upper part of the carrying bar C^1 , and it is held down on that bar by screwed rods K tapped into the underside of the plate A and extending through slotted holes K^1 in
- 45 the carrying bar, the rods having on their ends nuts K^2 bearing through a washer on the lower side of the bar. The slotted holes K^1 permit of the limited relative movement between the dumbturner plate A and its carrying bar C^1 necessary when separately ad-
- justing the plate A as hereinbefore described.
- What I claim is:—
1. In a dumbturner for sugar cane mills, having a carrying bar adjustably held by wedges acting between parts on the bar and projections on the mill housing; a dumbturner plate separate from the carrying bar, means for separately adjusting this plate relative to the rolls irrespective of the adjustment of the carrying bar, and means for holding the dumbturner plate on the upper surface of the carrying bar.
2. In the dumbturner forming the subject matter of the foregoing claim, a plate, the under surface of which is inclined from the front upwards towards the rear, a counterpart inclined portion on the upper surface of the carrying bar on which the plate rests, means for separately adjusting this plate relative to the rolls irrespective of the adjustment of the carrying bar, and means for holding the dumbturner plate on the upper surface of the carrying bar.
3. In the dumbturner forming the subject matter of claim 1 hereof, means for holding the dumbturner plate on the upper surface of its carrying bar comprising counterpart dove-tailed ribs and slots in the underside of the plate and in the top of the carrying bar.
4. In the dumbturner forming the subject matter of claim 1 hereof, means for separately adjusting the plate relative to the rolls irrespective of the adjustment of its carrying bar, comprising wedge faces in the upper surface of the plate at each end, inclined from the front downwards towards the rear, counterpart wedges engaging these wedge faces and engaging projections on the inner faces of the housings, adjusting rods connected with these wedges and extending out to the front of the mill, similar adjusting rods extending from the rear of the dumbturner plate at each end to the rear of the housings, and means for securing these rods.

In testimony whereof I have signed my name to this specification.

CHARLES McNEIL.
